A. H. DODGE

HANGER FOR SLIDING DOORS

Filed April 12, 1924

UNITED STATES PATENT OFFICE.

ARTHUR H. DODGE, OF NEW YORK, N. Y., ASSIGNOR TO THE J. G. WILSON CORPORATION, OF NEW YORK, N. Y., A CORPORATION OF VIRGINIA.

HANGER FOR SLIDING DOORS.

Application filed April 12, 1924. Serial No. 705,972.

This invention relates to sliding doors, and particularly to hangers therefor.

An object of the invention is to provide a sliding door hanger having improved provision for preventing the accidental removal of the door from its track.

Another object is to provide a strong, sturdy hanger which is simple in construction, and which also may readily be disassembled to inspect or repair the same.

An important feature of the invention is the provision in a hanger of a frame so shaped that it will prevent the removal of the door from the track by a vertical movement, preferably at all times but particularly when the door is closed.

Other important features are the provision of a hanger which cannot be disassembled when in its position on the track, but which may be readily disassembled when removed from the track and the provision in the hanger of means for adjusting the height of the door from the floor.

The invention is particularly useful when applied to fire doors, inasmuch as it insures that the door will remain closed in time of fire, when its opening would be at once most harmful in its effects and most probable to occur. When there is a fire on one side of the door, for example, the door will be expanded by the heat of the fire and the door and its mountings will tend to be warped or shifted so as to cause the door to be lifted off its track unless positive means to hold it in place are provided. Again, if the retentive action of the hanger is made to depend upon any pins, screws, or other unsubstantial members, the heat of the fire will tend to melt or to warp these members and thus to destroy their effectiveness. Moreover, when screws are employed to prevent the removal of the door, there is a tendency on the part of the workmen who set the door in place to omit to insert the screws, which omission will in all likelihood not be discovered until a fire has moved the door off of its track and caused great damage to the property which would otherwise have been protected by the door.

These disadvantages in certain fire doors which are used at the present time are overcome by my invention, which provides a sturdy hanger having as an integral part thereof the member which obstructs the ver-

tical movement of the door and prevents it from being removed from its track.

Other purposes, features and advantages of the invention will appear from the following description taken in connection with the accompanying drawings, which show one embodiment of the invention as applied to a fire door.

Fig. 1 illustrates a fire door embodying the invention;

Fig. 2 is a side view of a hanger therefor shown partly in cross section;

Fig. 3 is a front view of the hanger.

Fig. 1 shows a fire door 5 of any suitable construction slidably mounted by means of hangers 6 on a track 7 extending above an opening 8 in a fireproof wall 9. The track 7 is sloped toward and over the opening 8 so that when the door is not held open it will slide along the track to cover the opening. The door is preferably shaped with its top inclined to conform with the slope of the track, and is normally maintained open by means of a weight 10 on the end of a chain 11 which extends over a pulley 12 and is fastened to a brace 13 on the door 5.

In the chain, near the narrower end of the door, is a fusible link 14 which in case of a fire on either side of the door will be melted so as to release the door and allow it to slide closed. Other door releasing means, either immediately or remotely controlled, may obviously be used. A stud 15 set in the floor outside of the door and carrying a roller 16 acts to prevent outward movement of the door. As long as this stud is in place, the construction of the hanger to be described below will prevent the door from being moved from the track. A pair of stops 17 are fastened to the wall 9 to prevent the door from sliding past the opening 8 or beyond the stud 15. On the track 7 are a pair of projections 18 positioned under the hanger 6 when the door rests against the stops 17, shown in Fig. 2 as the heads of bolts 19 used to fasten the track on the wall.

The hanger 6 illustrated in Figs. 2 and 3, comprises a hook-shaped frame 20 fastened at its end 21 to the door 5 by bolts 22. The upper surface of the end 21 is sloped inwardly and is so positioned below the track 7, that when the door is raised vertically the hanger will still be held on the track by the flanges of a sheave to be described below,

but that, when the door is moved outwardly from the wall, the distance between the bottom of the track and the inner sloped-off portion of the end 21 will be sufficient to allow the removal of the sheave from the track. To permit this removal, the track should be set out from the wall enough so that the hook of the frame 20 may be moved toward the wall, and the flanges of the sheave 25 should be beveled in the manner shown. A saddle 24 is slidably held in the hook of the frame 20. A sheave or roller 25 turns upon a journal 26, which is slidably fitted through the sides of the saddle. The sheave 25 comprises a bushing 27 in which a groove 28 is provided to retain lubricating material. The sides 29 of the saddle are bent over the hook of the casting so as to prevent the saddle from being slid horizontally out of the hook. The sheave 25 is adapted to ride on the track and is set thereupon by a suitable movement of the door before the stud 15 is fastened in the floor outside the door.

In order to further insure against the sheave being lifted off the track by the vertical movement of the door when it is closed, a shoulder 30 is formed on the frame 20 so as to be beneath the projection 18 when the door is against the stops 17. The position 30 of this shoulder may, of course, be varied in accordance with the requirements of the door. It may be formed nearer the track 7 and the bolt 18 in case it is desired to more effectually prevent the raising of the door, and it may be placed further away from them if it is desired to more effectively insure against the catching thereof against the bolt 18 when the door is slid into closed position.

In order to allow the height of the door to be adjusted when it is put in place or at any time thereafter when the shifting of the floor or the wall or the sagging of the door renders this necessary, an adjustable screw 35 is inserted in a threaded opening in the top of the hook of the casting. On the screw is an annular shoulder 36 to take the thrust of the saddle and a reduced portion 37 extending into the saddle. The screw 35 may be provided with a head 38 to more readily allow its adjustment. In order to lock the screw after the height of the door has been adjusted and in order to hold the saddle and the sheave within the hook of the frame 20 while the door is being set upon the track, a set screw 39 is provided in the top of the saddle and is positioned so that it may be set into a groove 40 on the reduced end 37 of the screw 35. The employment of the adjusting means above described enables the track 7 to be set in any convenient position in the wall and the door to be adjusted to conform with this position. For example, the wall to which the track is to be secured often has obstructions such as projections

formed on the wall or reinforcing means for the wall which prevent the track from being attached to the wall in a position exactly in accordance with the height of the door. By the use of my adjusting means, the track may be placed on the wall so as to avoid all such obstructions without the necessity of altering the size of the door to conform with the position of the track. Furthermore, when the door is in place the disassembly of a hanger of the construction shown by fire or other causes is practically impossible, though the hanger may be readily disassembled after the door is removed from the track.

If, for any reason, it is desired to remove the door from the track, the stud 15 must first be removed from the floor and the bottom of the door is then swung outwardly about the points of engagement of the sheaves 25 with the track 7 until the ends 21 of the frames 20 are out from below the track. The door is then raised so that the flanges of the sheaves will clear the track. The frame, the sheave, and the saddle of each of the hangers 6 are so constructed that even after the door is removed from the track and the set screw 39 loosened, the hanger cannot be disassembled until the journal 26 has been slid out of its bushing 27. An opening 42 is provided in the frame at such position that it will normally be opposite the projection 18, but when the sheave rests on the end 21 of the frame it will be opposite the journal 26 to more readily enable the removal of the journal by the insertion of a tool through opening 42. The removal of the journal releases the sheave from the saddle, which is then raised and the sheave slipped out of the frame, after which the saddle may be again slid downwardly and removed.

The permanent construction of the hanger is exceedingly important when the hanger is likely to be exposed to fire or other causes which would tend to disassemble hangers of a less permanent character. The invention is, of course, not limited to the particular embodiments thereof illustrated and described.

What I claim as new is—

1. In a door hanger for sliding doors, a frame having a hook-shaped portion at one end thereof and an offset portion at the opposite end thereof located opposite the recess between the sides of the hook-shaped portion, a sheave, a sheave saddle slidably mounted in the hook-shaped portion of the frame, the length of the radius of the sheave together with the length of the sheave saddle being greater than the distance between the end of the hook and said offset portion from the frame, whereby the sheave saddle and sheave are prevented from removal from the frame until the sheave is

removed from the saddle, and means permitting removal of the sheave from the sheave saddle only when the sheave and saddle occupy a certain position in the frame.

2. In a sliding door hanger, a frame having a hook-shaped portion, a sheave saddle and sheave slidably mounted within the hook-shaped portion, a shaft on which said sheave is mounted, said shaft being retained in position by engagement of its ends with the walls of the hook-shaped portion of the frame, the frame having an opening through which, when the sheave saddle has been moved from its normal position to a certain other position in the frame, into which it is movable while the frame is attached to a door, the shaft may be removed from the sheave and sheave saddle to permit the disassembly of the hanger.

3. In a door hanger for sliding doors, a frame having a hook shaped portion, a saddle slidably mounted in the hook shaped portion of the frame, a sheave rotatably mounted in the saddle, and means on the frame for preventing the saddle and sheave

from being removed from the frame while the saddle and sheave are in assembled relation.

4. A frame having a hook shaped portion, a saddle slidably mounted in the hook shaped portion of the frame, a sheave rotatably mounted on the saddle, means for preventing the saddle and sheave from being removed from the frame while the saddle and sheave are in their assembled relation and means for enabling the frame and saddle to be disassembled while the frame is attached to a door.

5. In a door hanger, a frame having a hook-shaped portion and an offset on the same side of the frame as said hook-shaped portion for engagement with the track to prevent derailment, a sheave saddle slidably mounted on said frame, a sheave rotatably mounted on the saddle, and means for adjusting the saddle to adjust the distance of the sheave from said offset.

Signed at New York city, New York, this 10th day of April, 1924.

ARTHUR H. DODGE.
